UNITED STATES PATENT OFFICE

DAVIS MARINSKY, OF NEW YORK, N. Y.

SEPARABLE FASTENER

Application filed March 3, 1930. Serial No. 432,698.

This invention relates to fastening devices involving two stringers, each stringer having a series of projecting coupling elements arranged at one side edge thereof and adapted to be interengaged and interlocked by a slider movable longitudinally of the stringers in the movement of said slider in one direction and to be separated in the movement of the slider in the opposite direction; and the object of the invention is to provide a device of the class specified, the coupling elements of which are formed from strips of wire or other material, the end portions of which are preferably pronged to pierce a mounting or attaching strip preferably at spaced intervals in attaching said elements to the strip in the formation of said stringers and further in the forming of the central portion of said strips, coupling loops or members which project beyond the edge of the mounting strip and upon which the slider is movable; a further object being to provide a device of the class specified wherein a folded mounting strip may be employed or a strip provided with one or more reinforcing cords or strands arranged at the edge portion to which the coupling elements are attached; a further object being to provide a device of the class specified wherein the side edges of the slider are free to ride upon that part of the elements arranged upon the mounting strip thus eliminating the frictional wear on said strip which is commonly experienced in other devices of this class; a still further object being to so arrange the end portions of each element upon the mounting strip and with respect to adjacent elements as to provide a slight clearance space, permitting the free flexure of the mounting strip and said elements in the use of the device; and with these and other objects in view the invention consists in a device of the class and for the purpose specified which is simple in construction, efficient in use and which is constructed as hereinafter described and claimed.

The invention is fully disclosed in the following specification, of which the accompanying drawing forms a part, in which the separate parts of my improvement are desig-

nated by suitable reference characters in each of the views, and in which:

Fig. 1 is a plan view of a part of a complete device illustrating the method of coupling and uncoupling the separate stringers. 55

Fig. 2 is a transverse sectional view on the line 2—2 of Fig. 1 and on an enlarged scale.

Fig. 3 is an enlarged plan view of a part of one of the stringers illustrating the arrangement of the coupling elements thereon. 60

Fig. 4 is a detail view illustrating the manner of forming the separate wire or other strands to provide pointed or pronged ends thereto.

Fig. 5 is a detail view of one of the coupling elements partially formed. 65

Fig. 6 is a transverse detail view of one stringer illustrating one of the coupling elements attached thereto and showing a modification; and 70

Figs. 7 and 8 are views similar to Fig. 6 showing other modifications.

My present invention relates to separable fasteners of the general class, such for example as disclosed in a prior patent of the United States granted to me October 13, 1925, and numbered 1,557,304. In Figs. 1 and 2 of the drawing, I have indicated at 10 and 10^a the separate mounting strips for the separate stringers of my improved device. These strips are composed of fabric of any kind or class and as shown in Fig. 2 consist of strips of fabric having woven therein cords or strands 11 and 11^a arranged longitudinally of one side edge of each of the strips 10—10^a. However, these strips may be formed with two strands 12 and 13 formed in a strip 10^b as seen in Fig. 8, or on the other hand a strip such as shown at 14 in Fig. 6, and 14^a in Fig. 7 may be employed, the latter strips being folded centrally and the free edges turned inwardly as seen at 14^b to provide a neat and finished attaching edge to said strips. 85

In my present invention, I provide each strip 10—10^a with a series of coupling elements 15—15^a respectively, the elements 15^a differing only from the elements 15 in that the free end portions thereof are hook-shaped in form as seen at 15^b, note Fig. 1, to form 90

interlocking engagement with the elements 15 to prevent separation of the separate stringers formed by the strips 10—10^a. For this reason, the brief description of one of the elements 15—15^a will apply to both.

5 In forming these elements a strand or strip of wire or other material is preferably cut to a predetermined length to form a workpiece such as indicated at 16 in Fig. 4 of the drawing, the shearing of the workpiece being such as to form pointed ends 16^a. This workpiece is fashioned centrally by a suitable machine or in any other desired manner to partially form a loop 17 therein and to arrange the pronged ends 16^a in angularly disposed relation to the adjacent part of the strip, and when so arranged and formed the pronged ends are moved toward each other and passed through the mounting strip 10—10^a, one end passing upwardly through the strip and the other downwardly therethrough as will be apparent.

As viewed in Fig. 3 of the drawing, the pronged end passing downwardly through 25 the strip 10 designated by the reference 18 is of greater length than the pronged end 19 passed upwardly through the strip so as to pierce the strip 10 at spaced intervals thus preventing the rupturing of said strip. 30 After piercing the strip, the pronged ends are bent and pressed upon the strip in the manner clearly seen in Fig. 2 of the drawing. In this operation, it will be understood that the strip 10—10^a as well as the strand 11—11^a 35 will be compressed and the end portions 18 and 19 will form a relatively flat bearing surface upon which the side edges 20 of a coupling slider 21 are adapted to operate.

It will also be noted that in the operation 40 of compressing the ends 18 and 19, the loop portions 17 of the respective devices 15—15^a will be completely formed and the cross section of the channel or channels of the slider 21 will be fashioned to conform with the separate members 15—15^a and said members collectively when coupled, especially at the forward or contracted end 21^a of the slider. The slider 21 is more or less of conventional 45 form, being of the unit cast type and employing the usual finger piece 22 movable longitudinally of a T-shaped elbow 23 arranged upon the central top portion of the slider.

In attaching the separate elements 15—15^a 50 to their respective mounting strips 10—10^a, it is preferred although not absolutely essential, that the ends 18—19 of one element be spaced to a very slight degree from the corresponding end of adjacent elements to provide free flexure of the complete stringers and especially of that part of the stringers to which the elements 15—15^a are attached. This clearance space is exaggeratedly shown 55 at 24 in Fig. 3 of the drawing. It will be understood that the length of the parts 18

and 19 upon the strips 10—10^a may be varied to suit the requirements in different types of devices of the class under consideration and especially the use thereof, but it is preferred that said ends be comparatively short in 70 order to produce in the completed device, a neat and finished appearance and to reduce the transverse dimensions of the interengaged coupling elements as they appear when coupled together. In this connection, the 75 size of the loops 17 may also be varied to suit the different uses of the device.

In Fig. 6 of the drawing, the structure shown in Figs. 1 to 3 inclusive is modified solely in the provision of the different type of mounting strip, the cords or strands 11—11^a being omitted. In Fig. 7 of the drawing the structure shown in Fig. 6 is modified simply in the formation of the loop 17, which instead of being substantially circular in form, is fashioned to form an outer semi-circular portion 17^a joining the ends 18^a—19^a in relatively straight vertical portions 17^b forming thereof square shoulders upon which the side edges of the slider are adapted to move, it being understood that the slider will be fashioned to conform with the cross sectional contour of the coupling elements shown in Fig. 7 of the drawing.

In Fig. 8 of the drawing, I have shown another modification wherein a strip 10^b has the cords or strands 12 and 13 therein or coupled therewith in any desired manner, and in this construction, it is preferred that one of the ends of the separate elements, for example, the end 19^b, be arranged to pierce the strip 10^b inwardly of the inner strand 13, whereas the end 18^b be arranged to pierce the strip 10^b inwardly of the strand 12 and outwardly of the strand 13, or in other words, 105 between said strands.

It will be understood that while I have shown certain forms of coupling elements and have indicated specific manners of attaching the same to the mounting strips of the separate stringers, that my invention is not necessarily limited to the structures herein shown and described, nor am I limited to the specific manner of forming the separate coupling elements, and various other changes 110 in and modifications of the construction herein shown and described may be made within the scope of the appended claims without departing from the spirit of my invention or sacrificing its advantages.

Having fully described my invention, what I claim as new and desire to secure by Letters Patent, is:—

1. A slide fastener device comprising a pair of stringers, each of said stringers consisting of a mounting strip and a plurality of coupling elements of loop form arranged in juxtaposition longitudinally of one side edge of said strip, the coupling elements of one stringer interlocking with the elements 125 130

- of a companion stringer and being coupled and uncoupled by a slider, movable longitudinally of said stringers, each of the elements of each stringer terminating in end portions piercing said strip in attaching the same thereto, said elements projecting from the edge of said strip and being arranged in longitudinally spaced relation. 5
2. A slide fastener device comprising a pair of stringers, each of said stringers consisting of a mounting strip, and a plurality of coupling elements of loop form arranged in juxtaposition longitudinally of one side edge of said strip, the coupling elements of one stringer interlocking with the elements of a companion stringer and being coupled and uncoupled by a slider movable longitudinally of said stringers, the elements of each stringer having portions piercing said strip in attaching the same thereto, said elements projecting from the edge of said strip and being arranged in longitudinally spaced relation, portions of said elements being of greater transverse dimensions than the thickness of said strip, and the portions of said elements attached to the strip being of different lengths whereby said portions will pierce said strip at spaced intervals. 10
3. A slide fastener of the class described, comprising a mounting strip, a plurality of coupling elements arranged longitudinally of one side edge of said strip, said elements having loop portions of greater transverse dimensions than the thickness of said strip, and projecting beyond the free edge of the strip, each element terminating in end portions piercing said strip and lying snugly thereupon. 15
4. A slide fastener of the class described, comprising a mounting strip, a plurality of coupling elements arranged longitudinally of one side edge of said strip, said elements having loop portions of greater transverse dimensions than the thickness of said strip and projecting beyond the free edge of the strip and terminating in end portions piercing said strip and lying snugly thereupon, said end portions being arranged on opposite side faces of the strip and the end thereof projecting and being compressed upon the opposed faces of the strip. 20
5. A slide fastener of the class described, comprising a mounting strip, a plurality of coupling elements arranged longitudinally of one side edge of said strip, said elements having loop portions of greater transverse dimensions than the thickness of said strip and projecting beyond the free edge of the strip and terminating in end portions piercing said strip and lying snugly thereupon, said end portions being arranged on opposite side faces of the strip and the ends thereof projecting and being compressed upon the opposed faces of the strip, and said end portions 25 piercing the strip at spaced intervals, the end
- portions of each element being in abutting relation to each other, and each of said elements being slightly spaced with respect to adjacent elements on said strip. 30
6. A slide fastener of the class described, comprising a mounting strip, a plurality of coupling elements arranged longitudinally of one side edge of said strip, said elements having loop portions of greater transverse dimensions than the thickness of said strip and projecting beyond the free edge of the strip, each element terminating in end portions piercing said strip and lying snugly thereupon, and said strip being reinforced at the edge thereof to which said elements are attached. 35
7. A slide fastener device of the class described comprising two stringers, each of said stringers consisting of a mounting strip to one side edge of which is attached a plurality of substantially similar coupling elements, means whereby the elements of one strip will interengage and interlock with the elements of a companion strip in forming said device, each of said coupling elements having attached end portions piercing said strip inwardly of the edge thereof and in spaced relation with reference to each other and being compressed onto the strip in securing the elements thereto, and the unattached portions of said elements projecting beyond the edge of said strip and being arranged in spaced relation with reference to each other and being of greater transverse dimensions than the corresponding dimensions of the compressed end portions thereof. 40
8. A slide fastener device of the class described comprising two stringers, each of said stringers consisting of a mounting strip to one side edge of which is attached a plurality of coupling elements, means whereby the elements of one strip will interengage and interlock with the elements of a companion strip in forming said device, each of said coupling elements having attached end portions piercing said strip inwardly of the edge thereof and in spaced relation with reference to each other and being compressed onto the strip in securing the elements thereto, the unattached portions of said elements projecting beyond the edge of said strip and being arranged in spaced relation with reference to each other and being of greater transverse dimensions than the corresponding dimensions of the compressed end portions thereof, a slider adapted to move longitudinally of the elements of said stringers in coupling and uncoupling the same, and shoulders formed on said elements adapted to be engaged by said slider. 45
9. A slide fastener of the class described, comprising two stringers, each of said stringers consisting of a mounting strip and a plurality of similar coupling elements attached to one side edge of said strip, said elements

projecting from the side edge of said strip and being adapted to interlock with the elements of a companion stringer in coupling said stringers together, and the coupling elements of each stringer having attached end portions of less transverse dimensions than the projecting portions of said elements and piercing said strip inwardly of the edge thereof and in spaced relation with reference to each other and being compressed on said strip in securing the elements thereto.

10. A device of the class described comprising a plurality of independently formed wire loop elements having pronged end portions, 15 a mounting member to one edge of which said elements are adapted to be attached, the pronged ends of said elements piercing said member inwardly of the edge thereof and extending through said member and being 20 compressed upon both side faces thereof in coupling said elements therewith, and the loop portions of said elements projecting beyond the edge of said member and being of 25 greater transverse dimensions than the corresponding dimensions of the attached end portions of said elements.

11. A device of the class described comprising a plurality of independently formed wire loop elements having pronged end portions, 30 a mounting member to one edge of which said elements are adapted to be attached, the pronged ends of said elements piercing said member inwardly of the edge thereof and extending through said member and being 35 compressed upon both side faces thereof in coupling said elements therewith, the loop portions of said elements projecting beyond the edge of said member and being of greater transverse dimensions than the corresponding 40 dimensions of the attached end portions of said elements, and the pronged end portions of said elements piercing said member at intervals spaced transversely with respect thereto, the attached end portions of each of 45 said elements being arranged in abutting relation and the end portions of one element being in spaced relation to the corresponding 50 end portions of adjacent elements.

12. A device of the class described comprising a plurality of independently formed wire loop elements having pronged end portions, 55 a mounting member to one edge of which said elements are adapted to be attached, the pronged ends of said elements piercing said member inwardly of the edge thereof and extending through said member and being compressed upon both side faces thereof in coupling said elements therewith, the loop portions of said elements projecting 60 beyond the edge of said member and being of greater transverse dimensions than the corresponding dimensions of the attached end portions of said elements, and a reinforcing strand arranged in the edge portion of said 65 member, to which said elements are attached.

13. A separable fastener of the class described comprising two stringers, each stringer consisting of a mounting strip and a plurality of coupling elements arranged and spaced longitudinally of one side edge of said strip, each of said coupling elements being fashioned from a relatively thin band, the central portion of which is fashioned to form a coupling loop having projecting, 70 pronged end portions, said pronged end portions being disposed at opposite sides of the strip and pierced therethrough at spaced intervals, and compressed onto the strip to form attaching portions lying flat and snugly upon opposite faces of said strip and of less transverse dimensions than the corresponding dimensions of said coupling loops.

14. A separable fastener of the class described comprising two stringers, each stringer consisting of a mounting strip and a plurality of coupling elements arranged and spaced longitudinally of one side edge of said strip, each of said coupling elements being fashioned from a relatively thin band, the central portion of which is fashioned to form 80 a coupling loop having projecting, 85 pronged end portions, said pronged end portions being disposed at opposite sides of the strip and pierced therethrough at spaced intervals, and compressed onto the strip to form attaching portions lying flat and snugly upon 90 opposite faces of said strip and of less transverse dimensions than the corresponding dimensions of said coupling loops, and the coupling loops of the elements of one stringer 95 being spaced apart a distance equal to the thickness of the elements of the companion strip, whereby when said stringers are 100 coupled together, the coupling elements of one stringer are in abutting and interlocked relation with respect to the elements of the other stringer.

15. A separable fastener of the class described comprising two stringers, each stringer consisting of a mounting strip and a plurality of coupling elements arranged and spaced longitudinally of one side edge of said strip, each of said coupling elements being fashioned from a relatively thin band, the central portion of which is fashioned to 110 form a coupling loop having projecting, 115 pronged, end portions, said pronged end portions being disposed at opposite sides of the strip and pierced therethrough at spaced intervals, and compressed onto the strip to form 120 attaching portions lying flat and snugly upon opposite faces of said strip and of less transverse dimensions than the corresponding dimensions of said coupling loops, the coupling loops of one stringer intermeshing and interlocking with the coupling loops of a companion stringer, a slider for coupling and uncoupling said stringers, and the width of 125 said slider being less than the combined width of the coupling elements on attached string- 130

- ers, so that the side edges of said slider are free to move said elements inwardly of the attached ends thereof.
16. A device of the class described comprising a mounting strip, one side edge of which is provided with a reinforcing strand imbedded therein, a plurality of wire loop elements having pronged, end portions attached to the reinforced edge of said strip, said pronged, end portions piercing the strip inwardly of said strand from opposite side faces thereof, and being compressed onto the strip and said strand to securely retain said elements against movement with respect to said strip, the loop portions of said elements projecting beyond the edge of said strip and being of greater transverse dimensions than the corresponding dimensions of the attached portions of said elements.
17. A separable fastener of the class described comprising two stringers adapted to be coupled and uncoupled, each of said stringers consisting of a mounting strip and a plurality of wire loop coupling elements, each element terminating in end portions piercing said strip and arranged longitudinally of one side edge thereof, the outer projecting portions of said elements being of greater transverse dimensions than said end portions, a slider movable along said stringers in coupling and uncoupling the same, and the side edges of said slider being arranged to operate over said parts and to engage said projecting portions in drawing the stringers together.

In testimony that I claim the foregoing as my invention I have signed my name this 28th day of February, 1930.

DAVIS MARINSKY.
